UNITED STATES PATENT OFFICE

2,587,896

BROACHING MACHINE

Emery C. Raehrs, Cincinnati, Ohio, assignor to
 The Cincinnati Milling Machine Co., Cincinnati, Ohio, a corporation of Ohio

Application July 3, 1950, Serial No. 171,801

4 Claims. (Cl. 90—33)

1

This invention relates to improvements in broaching machines and has particular reference to machines of the surface broaching type.

One of the objects of the present invention is the provision of an improved structure for determining presentation of the surface to be formed of a work piece to the broaching tool.

A further object of the present invention is the provision of improved means for controlling the movement of a work piece into broaching position and rigidly securing the same during the machining operation, properly to resist the lateral cutting thrust of the broaching tool.

A further object of the present invention is the provision in a duplex type broaching machine of improved control mechanism for effecting proper selective presentation and locking in working position of the respective work holding elements.

An additional object of the invention is the provision of improved readily adjustable cycle control means for effecting reversals of operation of the broaching elements in timed sequential relation to the movement of the work holding elements.

Other objects and advantages of the present invention should be readily apparent by reference to the following specification, considered in conjunction with the accompanying drawings forming a part thereof, and it is to be understood that any modifications may be made in the exact structural details there shown and described, within the scope of the appended claims, without departing from or exceeding the spirit of the invention.

Figure 1 is a front elevation of a broaching machine embodying the present invention.

Figure 2 is a fragmentary vertical sectional view as on the line 2—2 of Figure 1.

Figure 3 is a plan view with parts broken away of the work supporting and cutting portion of the machine.

Figure 4 is a fragmentary vertical sectional view through the operating mechanism for the work holders taken on the line 4—4 of Figure 2.

Figure 5 is a sectional view on the line 5—5 of Figure 4, and

Figure 6 is a vertical sectional view on the line 6—6 of Figure 4.

In the drawings in which similar characters of reference are employed to denote corresponding parts throughout the several views, the numeral 10 designates the bed or base of a conventional type duplex broaching machine having rising therefrom the column structure 11 provided with the pairs of ways 12 and 13 slidably supporting the broaching rams 14 and 15 carrying the cutting

2

broaches 16 and 17 for operation on the face of a work piece, such as indicated at 18. The bed or base portion 10 is formed with a horizontal section as at 19 provided with a first pair of ways 20 and a second pair of ways 21 on which are respectively mounted the work supporting tables or work carriers 22 and 23.

These ways, as illustrated in Figure 1, are of T-formation, interlocking with the gib plates 24 which restrain the tables against upward movement with respect to the ways. Suitable clamping means 25 interlock with the work piece 18 to secure the same in machining position on its supporting table.

In utilization of machines of this character it is customary that one work holding table or fixture such as the member 22 shown in Figure 3, is secured in advanced position locating the work-piece for engagement with the cutter 16 during the downward or cutting stroke of the ram 14 while the table or fixture 21 is retracted for unloading and loading purposes during the upward or non-cutting stroke of the ram 15 carrying the tool 17. It is preferable that the tables 22 and 23 be alternately shifted into tooling position in suitable timed sequence. It is further necessary that the table in tooling position be securely locked against any retracting movement due to the force reaction of the cutting tool or broach against the surface of the work piece.

The improved mechanism for effecting this positioning and locking of the work table will be best understood by reference to Figure 2 from which it will be seen that there is formed in the underside of the table 22 a kerf or recess 26 to receive one end of the link 27 mounted on the pivot pin 28.

The opposite end of this link is pivotally connected by a pin 29 with the forward end of link 30, in turn pivoted by pin 31 to the portion 19 of the bed, the links 27 and 30 thus providing a collapsible toggle mechanism. Additionally mounted on the pin 29 for control of this toggle is a third link 32 having its lower end connected by pivot 33 to a lug 34 of the control cam or eccentric 35 secured to one end of the shaft 36 as particularly illustrated in Figure 4.

The shaft 36 is rotatably supported by bearings 37 carried by the webs 38 secured to or integral with the bed portion 19. Intermediately, this shaft is provided with an actuating pinion 39 meshing with rack 40 on piston rod 41 which is reversely actuatable by piston 42 contained within the cylinder 43 secured in the bed as by bolts 44. Hydraulic conduits 45 and 46 couplable with

a suitable source of the hydraulic actuating medium (not shown) serve to control the reciprocation of the piston and thus the oscillation of pinion 39 and shaft 36.

At its opposite end shaft 36 is provided with a second cam or eccentric 47 having a lug 48 corresponding to the lug 34 on member 35. Pivot or crank pin 49 serves to couple the lower end of link 50 which corresponds with the previously described link 32 with the lug 48. Link 50 is, in turn, provided with the pivot 51 on which are mounted the links 52 and 53 forming a toggle, the link 53 being connected in its opposite end by pin 54 with the table 23. The outer end of the toggle link 52 is pivoted, like the link 30, to the forward portion of the bed by pivot pin 31.

It will be noted, particularly by reference to Figure 2, that the relationship of the cranks or eccentrics 34 and 48 is such that they are phased substantially 180 degrees, so that when the toggle comprising the members 27-30 is straightened to move the table 22 into its forward operative position the toggle formed by the members 52-53 is retracted or collapsed to shift the table 55 into a rearward or loading position. Correspondingly, on oscillation of shaft 36, the toggle 52-53 will be straightened, moving and locking the table 23 in its forward position while the table 22 is retracted.

For insuring exact correct positioning of the tables with respect to the broach carrying column 11, the column 11 is provided with the adjustable abutments 60, 61, 62, and 63. Table 22 is provided with the lateral lugs 64 and 65 carrying the threaded or otherwise adjustable abutments 66 and 67 for cooperation with the abutments 60 and 61. Lock nuts 86 and 87 serve to lock the abutments or stops 66 and 67 in adjusted position. Similarly, the table 23 is provided with the ears 68 and 69 carrying the threaded or otherwise adjustable abutments 70 and 71 for cooperation with the abutments 62 and 63 of the column. These parts, therefore, may be set accurately to determine the ultimate inward position of table 22 or table 23.

At the same time, to limit the movement of the toggle member to proper rectilinear alignment of the members 27-30 or 52-53 for best locking of the related work table in position, the frame portion 19 is provided with adjustable stops such as 72 for contact with the toggle mechanism, which stops are provided with lock nuts such as 88. Suitable hydraulic control mechanism for actuation of the broaches and piston 42, such, for example, as that shown in Patent 2,507,581, may be employed, primarily under control of the handles 73 and 74 pivotally mounted on the bed section 19. This hydraulic mechanism may include a reciprocable reversing valve or cycle control plunger 75 corresponding to the plunger 70 of the ram direction control valve 69 shown in said Patent 2,507,581. This valve plunger 75, as indicated in Figure 5, is provided with a double tapered head 76 engageable alternatively by the pulling dog 77 for effecting its movement in a left hand direction, or the pushing dog 78 for shifting the same in a right hand direction. These dogs are adjustably mounted as by bolts 79 having T heads 80 engaged in the annular T slot 81 formed in the periphery of the member 47. With the parts in the position indicated in the drawings, the table 22 is in its forward position and the valve plunger 75 has been shifted to the left. As the broach ram 14 completes its cutting stroke, suitable valve mechanism (not shown)

will cause introduction of hydraulic pressure into conduit 55, moving piston 42 downwardly while conduit 46 is connected with exhaust. This will effect a clockwise rotation of the cranks 34 and 48, breaking the toggle 27-30 to unlock and retract table 22 while closing the toggle 52-53, moving the loaded work table 23 to bring the work into tooling or cutting position and locking the table in its advanced position. As this movement is completed, dog 78 will engage the beveled inner or left hand face of plunger head 76, moving plunger 75 to the right and effecting a reversal of the effect of the hydraulic circuit as respects rams 14 and 15 so that ram 14 will be idly raised, while ram 15 moves its cutter 17 to effect a tooling or surfacing operation thereby on the workpiece 18. As this control circuit is illustrated in and as a part of Patent 2,507,581, and, in itself, forms no part of the present invention, a detailed illustration thereof has been deemed unnecessary.

What is claimed is:

1. A duplex broaching machine comprising a bed, column means rising from the bed and provided with spaced sets of ram guides, a pair of rams individual to the respective guides supported by the guides for reciprocation thereon with respect to the column, a work carrier individual to each ram, guides on the bed supporting each work carrier for movement toward and from its associated ram, a first toggle mechanism for effecting reciprocation of one of the work carriers toward and from its ram, a second toggle mechanism for effecting corresponding reciprocating movements of the other work carrier, and a control shaft rotatably supported by the bed having a pair of oppositely phased eccentric portions, a link connecting one of said eccentric portions with one of the carrier toggle mechanisms, a second link connecting the other of said eccentric portions with the other toggle mechanism, means for imparting oscillatory movement to the shaft, whereby the links will oppositely react on the respective toggle mechanisms simultaneously to effect an opening of one toggle mechanism and retraction of its carrier and a closing of the other toggle mechanism and forward movement of its associated carrier, a cycle control valve carried by the bed in juxtaposed relation to the shaft, and a dog element carried by the shaft in position for engagement with the cycle control valve to actuate the latter upon oscillation of the shaft.

2. A duplex broaching machine comprising a bed, column means rising from the bed and provided with spaced sets of ram guides, a pair of rams individual to the respective guides supported by the guides for reciprocation thereon with respect to the column, a work carrier individual to each ram, guides on the bed supporting each work carrier for movement toward and from its associated ram, a first toggle mechanism for effecting reciprocation of one of the work carriers toward and from its ram, a second toggle mechanism for effecting corresponding reciprocating movements of the other work carrier, and a control shaft rotatably supported by the bed having a pair of oppositely phased eccentric portions, a link connecting one of said eccentric portions with one of the carrier toggle mechanisms, a second link connecting the other of said eccentric portions with the other toggle mechanism, means for imparting oscillatory movement to the shaft, whereby the links will oppositely react on the respective toggle mechanisms simul-

aneously to effect an opening of one toggle mechanism and retraction of its carrier and a closing of the other toggle mechanism and forward movement of its associated carrier, a cycle control valve carried by the bed in juxtapositioned relation to the shaft, a dog element carried by the shaft in position for engagement with the cycle control valve to actuate the latter upon oscillation of the shaft, and abutment means carried by the bed for engagement with the toggle mechanism to limit the actuation of the toggle and thus the amount of rotation imparted to the shaft.

3. A duplex broaching machine comprising a bed, column means rising from the bed and provided with spaced sets of ram guides, a pair of rams individual to the respective guides supported by the guides for reciprocation thereon with respect to the column, a work carrier individual to each ram, guides on the bed supporting each work carrier for movement toward and from its associated ram, a first toggle mechanism for effecting reciprocation of one of the work carriers toward and from its ram, a second toggle mechanism for effecting corresponding reciprocating movements of the other work carrier, and a control shaft rotatably supported by the bed having a pair of oppositely phased eccentric portions, a link connecting one of said eccentric portions with one of the carrier toggle mechanisms, a second link connecting the other of said eccentric portions with the other toggle mechanism, and means for imparting oscillatory movement to the shaft, whereby the links will oppositely react on the respective toggle mechanisms simultaneously to effect an opening of one toggle mechanism and retraction of its carrier and a closing of the other toggle mechanism and forward movement of its associated carrier, a cycle control valve for controlling operation of the broach having an actuating portion disposed in juxtaposition to the shaft, a first dog carried by and oscillatable with the shaft, a second dog carried by and oscillatable with the shaft in substantially 180 degree phased relation with respect to the first dog, each of said dogs having an actuating portion engageable with the actuating portion of the cycle control valve for effecting movement of the valve in timed relation to the actuation of the respective toggles as determined by oscillation of the shaft.

4. A duplex broaching machine comprising a

bed, column means rising from the bed and provided with spaced sets of ram guides, a pair of rams individual to the respective guides supported by the guides for reciprocation thereon with respect to the column, a work carrier individual to each ram, guides on the bed supporting each work carrier for movement toward and from its associated ram, a first toggle mechanism for effecting reciprocation of one of the work carriers toward and from its ram, a second toggle mechanism for effecting corresponding reciprocating movements of the other work carrier, and a control shaft rotatably supported by the bed having a pair of oppositely phased eccentric portions, a link connecting one of said eccentric portions with one of the carrier toggle mechanisms, a second link connecting the other of said eccentric portions with the other toggle mechanism, means for imparting oscillatory movement to the shaft, whereby the links will oppositely react on the respective toggle mechanisms simultaneously to effect an opening of one toggle mechanism and retraction of its carrier and a closing of the other toggle mechanism and forward movement of its associated carrier, a cycle control valve for controlling operation of the broach having an actuating portion disposed in juxtaposition to the shaft, a first dog carried by and oscillatable with the shaft, a second dog carried by and oscillatable with the shaft in substantially 180 degree phased relation with respect to the first dog, each of said dogs having an actuating portion engageable with the actuating portion of the cycle control valve for effecting movement of the valve in timed relation to the actuation of the respective toggles as determined by oscillation of the shaft, and abutment means for limiting the respective closing movements of the toggle means and thus the extent of oscillation of the shaft in either direction of actuation thereof.
